(Cl. D34—5)

FIG. 1.

FIG. 2.

FIG. 1 is a top plan view of a gameboard showing our new design; and

FIG. 2 is a side elevational view thereof.

The characteristic feature of our design resides in a circular game board having the combination of a circular peripheral pathway from which six inner triangular pathways point toward a central square, with all but one of the inner pathways in the configuration of a truncated triangle, all as shown.

The dominant features of our design reside in the portions shown in full lines.

We claim:

The ornamental design for a game board, as shown and described.
